UNITED STATES PATENT OFFICE.

HEINRICH WENZEL, OF BERLIN, GERMANY.

GUN.

Application filed May 28, 1925, Serial No. 33,516, and in Germany June 6, 1924.

My invention relates to improvements in guns, and the object of the improvements is to provide a gun comprising a body part adapted to have barrels and breech mechanisms for cartridges of different calibers mounted thereon, and with this object in view my invention consists in constructing the gun of two parts adapted to be readily connected with or disconnected from each other, one of said parts comprising the butt, the stock, a pipe and certain other elements, and the other removable part comprising the barrel and the breech mechanism. Therefore, I am enabled to use the same body part together with removable parts for firing cartridges of different dimensions and qualities. For example I am enabled to reconstruct a gun comprising a small caliber barrel and breech mechanism into a gun for cartridges of larger calibers. My invention also relates to the construction and relative arrangement of certain details of the gun and simple means for connecting the said main parts thereof, which parts are so connected that the oscillations of the barrel are not interfered with and a highly efficient gun is obtained. In my improved gun the barrel is manufactured from cast steel, and it is provided with a reinforcing sleeve carrying all the said parts required for connecting the exchangeable parts with the body of the gun.

For the purpose of explaining the invention an example embodying the same has been shown in the accompanying drawings, in which the same reference characters have been used in all the views to indicate corresponding parts. In said drawings,

Fig. 1, is a sectional elevation of the gun with a part of the barrel and the butt broken away,

Fig. 2, is an elevation partly in section showing the removable part of the gun,

Fig. 3, is a sectional elevation showing the body of the gun with the barrel and associate parts removed,

Fig. 4, is an elevation in section taken on the line 4—4 of Fig. 3,

Fig. 5, is a section taken on the line 5—5 of Fig. 2,

Fig. 6, is an elevation showing the front part of the bolt,

Fig. 7, is an elevation looking from the left in Fig. 6, and

Fig. 8, is a sectional elevation taken on the line 8—8 of Fig. 2.

In the example shown in the drawings the body part of the gun consists of the butt 13, the stock 130, a pipe 15 carried by the stock and connected therewith by a screw 131, a tubular body 14 fixed to the stock 130 by means of a screw 132 and formed with an annular shoulder 140 providing a seat for the rear end of the pipe 15, and a sleeve 16 in axial alignment with the pipe 15, and carrying the rear sight 160, the front sight 161 being provided on the pipe 15. Further, the body part of the gun carries the trigger mechanism. The tubular body 14 is provided at its front part with a bore 14^e the diameter of which is equal to the outer diameter of the barrel 1. At the median part of the said body the bore 14^e thereof is enlarged in diameter to accommodate a reinforcing sleeve 2 of the barrel, and at the rear of the part 14^e the body is formed with a chamber 14^a, the said chamber being bounded at its rear end by an internally directed flange 14^d. The flange 14^d is formed at opposite sides with recesses 14^b, as is shown in Fig. 4. The sleeve 16 is formed at its top end with an internal groove 16^a. At its front end the pipe 15 contains a bushing 17 providing a support for the front end of the barrel 1.

The parts to be exchangeably mounted on the body part so far described consist of the barrel 1 provided with the reinforcing sleeve 2. The said sleeve is formed with a collar 2^b and, at the rear thereof, with screw-threads 20, a sleeve 3 being screwed on the said screw-threads, which sleeve is formed with an elongated portion 30 of reduced diameter. To the rear end of the said reduced portion a ring 3^a is fitted, which ring is provided with holes (not shown) for inserting a suitable tool for screwing the ring 3^a and the sleeve 3 on the screw-threads 20. Between the sleeve 3 and the ring 3^a a sleeve 3^b is located which is formed at its front end with lateral lugs 3^c corresponding to the recesses 14^b of the flange 14^d. To the rear end of the reinforcing sleeve 2 a tubular member 4 providing a bolt race-way is fixed by means of pins 22 and 23, and the said sleeve is formed with a loading aperture 4^b and a nose 4^a adapted for engagement with the groove 16^a of the sleeve 16. The reinforcing sleeve 2 is formed at its rear end with a bottom extension 2^a in the form of a gutter providing a support for the cartridge passed

through the aperture 4^b. From the said gutter 2^a the cartridge is pushed into the barrel by advancing the bolt 5. On the said bolt the usual extractor 6 is mounted, which, after pushing the cartridge into the barrel, engages the flange thereof with its claw 6^a, a shoulder 6^b of the extractor bearing on the rear face of the cartridge. The rear end 6^c of the extractor 6 is in the path of the front end 80 of the firing pin 8 fixed to a slide 7 and acted upon by the usual spring 81. When the firing pin is thrown forwardly by the spring 81 its front end 80 strikes on the rear end 6^c of the extractor 15 so that the shoulder 6^b causes marginal ignition of the cartridge. The firing mechanism so far referred to does not form a part of the invention and I deem it not necessary to describe the same more in detail.

20 For assembling the gun the system composed of the barrel 1, the reinforcing sleeve 2, the tubular member 4 and the bolt 5 is inserted from the rear into the body 14, the pipe 15 and the bushing 17, the nose 4^a engaging the groove 16^a of the sleeve 16, so that rotation of the system around the axis of the barrel is impossible. Now the barrel 1 is in the position shown in Fig. 1 and it is slidably held within the bushing 17.

25 The lugs 3^c of the sleeve 3^b are passed through the recesses 14^b of the flange 14^a and turned through an angle of 90°. When inserting the said system the collar 2^b of the reinforcing sleeve 2 bears on the shoulder 142 of the chamber 14^a. To prevent axial displacement of the system means are provided for locking the same as against axial displacement in the opposite direction which means consist of the screw-threads 20 and 30 the sleeve 3^b engaging the same, the head of the said sleeve being turned by means of a suitable tool so far that the lugs 3^c are in close engagement with the shoulder 143 of the chamber 14^a. In the construction 35 shown in the drawings an ejector may be dispensed with. When moving the bolt rearwardly the extension 2^a is in frictional engagement with the bottom part of the cartridge, which is thereby rocked upwardly 40 and ejected.

In the example shown in the figures, the support for the cartridge, that is the gutter 2^a, is made integral with the reinforcing sleeve 2. But I wish it to be understood 45 that my invention is not limited to this feature, and that the said gutter may be made integral with the barrel. By constructing the gutter in the manner described the tubular member 4 is simple in construction, because only a concentric bore need be provided. The front part of the bolt 5 fitted on the gutter so as to provide an effective safeguard as against back firing, as will be understood from an inspection of Figs. 60 6 and 7. The nut 7 of the firing pin is

formed at its rear with a cylindrical lug 7^a adapted to be used as a tool for turning the sleeve 30. In order that the removable part of the gun can be used in connection with other guns of larger caliber, its shape, arrangement and dimensions are such as to correspond to such guns. For inserting the said removable system into another gun the sleeve 30 is unscrewed by means of the aforesaid tool into the position with the lugs 3^a 75 in alignment with the recesses 14^b, whereupon the whole system is retracted rearwardly and away from the body of the gun. Now the system may be inserted into a gun of smaller caliber and locked therein by means of the sleeve 3^b.

While in describing the invention reference has been made to a particular example embodying the same I wish it to be understood that my invention is not limited to the construction shown in the drawings, and that various changes may be made in the general arrangement of the apparatus and the construction of its parts without departing from the invention.

I claim:

1. A gun, comprising a body part and a part removably mounted thereon, said body part including the butt, the stock, a tubular body connected with the stock and a sleeve, and said removable part including the barrel and the bolt raceway removably mounted within said tubular body and sleeve, said sleeve and bolt raceway being connected with each other for preventing rotation of the removable part.

2. A gun, comprising a body part and a part removably mounted thereon, said body part including the butt, the stock, a tubular body secured thereto, a pipe secured to said tubular body and provided at its outer end with guiding means for the barrel, and a sleeve fixed to the stock at the rear of said tubular body, and said removable part including the barrel and a tubular member 105 fixed thereto and both loosely mounted in said pipe, tubular body, and sleeve, said barrel being loosely guided at its front end in the front end of said pipe.

3. A gun, comprising a body part and a part removably mounted thereon, said body part including the butt, the stock, a tubular body fixed to said stock and formed at its rear with an axial chamber provided at its front and rear with shoulders, and rear supporting means, and said removable part including the barrel and a tubular member fixed thereto and both removably mounted in said tubular body and rear support, said barrel carrying a lug and an axially shiftable clamping member disposed within said chamber and in clamping engagement respectively with said front and rear shoulders.

4. A gun, comprising a body part and a

- part removably mounted thereon, said body part including the butt, the stock, a tubular body fixed to said stock and formed at its rear with an axial chamber provided at 5 its front and rear with shoulders, and a rear supporting sleeve formed with an axial groove, and rear supporting means, and said removable part including the barrel and a tubular member fixed thereto and both removably mounted in said tubular body and 10 rear support, said barrel carrying a lug and an axially shiftable clamping member disposed within said chamber and in clamping engagement respectively with said front and rear shoulders, and said tubular member carrying a nose engaging in said groove.
5. A gun, comprising a body part and a part removably mounted thereon, said body part being composed of the butt, the stock, 15 a tubular body, and a sleeve, said tubular body and sleeve being secured to said stock
- and in axial alignment with each other, and said removable part comprising a barrel, a reinforcing sleeve therefor, and a tubular member fixed to said sleeve and constructed for providing the bolt raceway.
6. A gun, comprising a body part and a part removably mounted thereon, said body part being composed of the butt, the stock, a tubular body, and a sleeve, said tubular 20 body and sleeve being secured to said stock and in axial alignment with each other, and said removable part comprising a barrel, a reinforcing sleeve therefor and a tubular member fixed to said sleeve and constructed 25 for providing the bolt raceway, said barrel having a trough shaped rear extension disposed within said raceway in position for forming a support for the cartridge.

In testimony whereon I hereunto affix my 40
signature.

HEINRICH WENZEL.
